UNITED STATES PATENT OFFICE.

WILLIAM W. WATSON, OF JAMESTOWN, NEW YORK.

KNOCKDOWN ROLLER-SCREEN.

1,113,721.

Specification of Letters Patent. Patented Oct. 13, 1914.

Application filed July 18, 1913. Serial No. 779,848.

To all whom it may concern:

Be it known that I, WILLIAM W. WATSON, a citizen of the United States, residing at the city of Jamestown, in the county of 5 Chautauqua and State of New York, have invented certain new and useful Improvements in Knockdown Roller-Screens, of which the following, taken in connection with the accompanying drawings, is a specification.

The invention relates to roller window screens; and the object of the improvement is to provide a roller screen construction which is knock-down in its arrangement, so 15 that the parts may be easily taken apart and put together, the different parts fitting one another so perfectly that they may be shipped knock-down and quickly and easily adjusted to the window frame, and when 20 so adjusted the springs may be released and they are then in correct tension for the parts and ready for operation; and the invention consists in the combination and arrangement of the parts as shown in this 25 specification and the accompanying drawings and pointed out in the claims.

In the drawings, Figure 1 shows a front elevation of the lower portion of a window frame having a roller screen mounted thereon with the sash in the raised position and the screen covering the space below the sash. Fig. 2 is a perspective view of the lower end of one of the side cases of the screen frame showing the arrangement of the lower portion 35 of the same for the reception of the end of the crosswise or sill casing containing the spring roll; and Fig. 3 is a perspective view of the end of said crosswise casing which fits into the lower end of the side 40 case shown in Fig. 2; and Fig. 4 is an elevation of said lower end of the side casing showing the position of the different parts. Figs. 5 and 6 show perspective views of the 45 guide piece for the end of the operating tape within the side case; and Fig. 7 is a sectional view of the guide piece at line X-X in Fig. 6, showing the manner of attaching the tape. Fig. 8 is a perspective view of the opened side case showing the tape and 50 pulleys for raising and lowering the screen fabric; and Fig. 9 is a perspective view of

the closed side case and a portion of the screen and spring roll and case, the screen being partially unrolled, and the top cap of the side case is raised from the upper 55 end of the same. Fig. 10 is a lengthwise sectional view of the side case at line Y-Y in Fig. 9, showing the construction and arrangement of the parts; a portion of the tape being broken away. Fig. 11 is an elevation of the open side case shown in perspective in Fig. 8, with the guide piece for the end of the operating tape started downward in its proper channel. Fig. 12 is an elevation of the spring roll showing the 60 locking opening for the springs. Fig. 13 is an elevation of the connecting tube for the tension springs showing the compensating notch in each end for the end of the operating spring. Fig. 14 is a perspective 65 view of one of the end plugs for the spring roll removed from the tubular roll; and Fig. 15 is an end elevation of the same, showing the square opening therein to receive the square pin or shaft on the pulley 70 at the lower end of the side case. Fig. 16 is an elevation of one of the tension springs. Fig. 17 is a lengthwise sectional view of the 75 spring roll with the central portions broken away, showing the end plugs with the connective tube therebetween and the tension springs attached to said tube and plug at one end and to the roller at the other. Fig. 18 is a perspective view of the wrench for 80 setting the tension of the springs by turning the tubular end plugs in the spring roll. Fig. 19 is a simple locking plate for holding the tape in the rolled position until all the parts of the screen are assembled. Fig. 20 is an elevation of a pulley showing tape attachment thereto.

Similar numerals of reference refer to corresponding parts in the several views.

The numeral 20 designates the window casing and the numeral 21 the window sash 85 and glass.

The knock-down roller screen mechanism consists of two side cases 22 which are precisely alike excepting they are rights and lefts, the lower ends 23 opening toward one 100 another, as shown in Fig. 1. A crosswise roll case 24 connects the side cases 22, as

hereinafter set forth. Each of the side cases 22 consists of the lengthwise channel strip 25 and a cover strip 42, which are attached to the window frame or casing 20 by screws 26 through both strips. The operating pulleys and tape are operably mounted within the channel strip 25. Said pulleys and tape consist of a top pulley 27 which is revolvably mounted on a stud 28. A second pulley 29 is revolvably mounted on a stud 30, which stud is attached to the inner side of the channel strip 25. The pulley 29 has a short square shaft or pin 31 extending therefrom toward the opposite side case. An operating tape 32 is attached to pulley 29 over two spaced pins 32 by extending around and back beneath itself in locking engagement, and then up over the top pulley 27. It is then attached to a guide piece 33 which is slidably mounted within a channel or chute 34 in channel strip 25, the channel being formed by means of a sheet metal strip 35 which is attached lengthwise of the inner side of the channel strip 25. The pulley 29 must be of sufficient size to receive over half of the operating tape when the screen is unrolled from the spring roll. Two guide pulleys 36 are preferably revolvably mounted on suitable studs, one just above bottom pulley 29 and the other below top pulley 27 and have channeled edges to hold the tape in line.

The guide piece 33 is preferably made in the form of a channel piece with the two cross pins 37 therein a spaced distance apart, the same as in pulley 29, to receive the end of the tape 32 around the same in the locking attachment shown in Figs. 7 and 20, which holds said tape end firmly yet is easy of attachment thereto. A slot 38 is provided through the inner side of the channel guide strip 33 to receive the headed strip or pin 39 therethrough for attachment to the top cross piece 40 of the screen fabric 41. The strip 39 is insertible into an opening in the end of the top cross bar 40.

The lengthwise partition or guide strip 35 also serves as a separator or spacer between the channel strip 25 and the cover strip 42. The two strips 25 and 42 are attached to one another by means of screws 43 which preferably engage through suitable holes in the cover strip 42 with the brackets 44 in the channel strip 25 so that by the removal of the screws 43, the interior of the channel strip 25 and the operating tape 32, the pulleys 27 and 29 are quickly exposed for repair. The cover strip 42 is formed with oppositely turned flanged lengthwise edges, one flange 45 fitting over the outer flange edge of the channel strip 25, and the other flange edge 46 is held by the screws 43 a spaced distance from the inner flange edge 47 of the channel strip 25 to thereby form the open channel slot 48 between the flanges 46 and 47 to receive therein the pin 39 in

the guide strip 33 as it is moved upward and downward in the raising and lowering of the screen 41.

A cap 49 is provided for the upper end of the side case 22. The cap 49 fits closely over the upper ends of the two strips 25 and 42, holding them firmly in position. The lower end of the cover strip 42 has the open housing 23 formed thereon for the reception of the crosswise housing or roll casing 24 for the spring roller 52 to which the screen fabric 41 is attached and upon which it is rolled. The casing part 23 is attached at its upper end to the cover strip 42 by means of the upturned lap 53 which is welded or otherwise attached to the flange 46 of the cover strip 42. The inner portion of the said upper end of the part 23 is turned downward in a tube 54 and welded, as shown in Figs. 2 and 4, to receive therein the end 55 of the binding wire in the upper edge of the housing 24. The end of the housing 24 is formed to fit within the part 23 so that it may be slipped into the same, the end 55 of the binding wire entering tube 54 thereby holding the side casing 22 and the roller casing 24 firmly together and in position within the window frame, yet allowing a slight adaptation to the window frame. The housing or casing 24 is simply a tubular casing having preferably its rear side 56 extending only part way up so as to permit the insertion of the roll 52 with the screen fabric 41 attached and rolled thereon and providing an opening for the free movement of the screen fabric 41 as it rolls out from and into the casing 24 from the roll 38.

The roll 52 is preferably made from sheet metal tubing. An end plug 57 is provided for each end of the tubular roller 52 formed to turn freely within the tube 52, and has a square hole 58 in the outer end to receive therethrough the square or rectangular pin or shaft 31 on pulley 29 so as to turn with the pulley 29 in operating the tape 32 and the screen 41.

The inner end 59 of the plug 57 is diminished in size to fit the end of a connecting tube 62 and has the slot 60 therethrough to receive the end 50 of the tension coil spring 61 in locking engagement. The connecting tube 62 has compensating notches 63 therein into which the ends 50 of the locking springs 61 extend crosswise thereof in order to give a partial rotating compensating movement for the tube 62 and the tension spring 61 so that they will automatically adapt themselves to the movement or changes in the tape 32 and screen fabric 41. A series of holes 64 are also provided in the tubular end plugs 57 for holding the tension of the springs 61 when said tension has been adjusted as desired, a series of holes 65 being provided in the roller 52 in line with holes 64 to receive a pin 73 therethrough in lock-

ing engagement to hold said spring tension until it is desired to release the same after the screen and casing have been properly set up, an opening 74 being provided in the case 21 through which the pin 73 may be removed. The opposite end 51 of the tension spring 61 from that engaging the slot 60 and compensating notch 63, is inserted through a small opening 67 in the roller 52 to there-
 5 by attach one end of said spring 61 firmly to the tubular roller 52 while the other is attached to the inner end of the tubular plug 57.
 The cross piece 40 for the upper end of the screen fabric 41 is preferably formed of
 10 an angle piece and a channel strip of sheet metal 68 which fits the angular projection of the cross piece 40 and binds thereon a strip 69 preferably of rubber to form a weather strip which presses against the un-
 15 der side of the sash 21 thereby insuring the closing of the space between the cross bar 40 and the sash 21.
 The wrench 66 and locking plate 70 are provided for assembling or setting up the
 20 roller screen mechanism and to insure the correct tension thereon, and are used in the following manner: The wrench 66 is used to turn the end plug 57 until the proper tension is obtained for the tension spring 61
 25 and a pin 73 is then inserted through the openings 64 and 65 thereby holding said spring 61 at the tension desired. Each of the tension springs 61 having thus been ad-
 justed and the screen fabric 41 having been
 30 attached to the roller 52 by soldering or other suitable means and the screen fabric rolled on the roller 52, the roller is inserted within the housing 24 and said housing and roller are then ready for shipment.
 35 The tape 32 is attached to the guide piece 33 at one end and to the roller 29 at the other and rolled on said roller 29 so that the guide piece 33 preferably touches the upper end or cap 49 of the side case 22, as
 40 shown in Fig. 8, said guide pieces 33 having the attaching strip or pin 39 inserted through the slot 38 and extending out through the slot 48 for insertion in the end of the cross bar 40. The cover strip 42 is
 45 then attached to the channel strips 25 by screws 43, and the locking plate 70 is inserted through the lower end of the side case, the notch 71 in the locking plate 70 fitting closely onto the square pin 31 thereby hold-
 50 ing the tape around the pulley 29 ready to receive the tension from spring 61. The cross bar 40 is attached to the upper end of the screen fabric 41 preferably before it is attached to and rolled upon the roller 52.
 55 The two side cases 22 and the roller case 24 are then ready for shipment with the entire roller screen mechanism therein, and it is apparent that these three parts can be placed in an exceedingly small compass as com-
 60 pared with the set-up screen, while all the

parts are ready for setting up within the window frame 20.

When it is desired to set-up the screen within the window frame 20 the roller hous-
 65 ing 24 is inserted within the side cases 22 at each end thereby inserting the shafts 31 which are attached to the rollers 29 within the square openings 58 in the revoluble
 70 plugs 57 in each end of the roller 52. The locking plates 70 are then withdrawn and 75 the pins 73 are also withdrawn from the holes 64 and 65 thereby applying the ten-
 75 sion of the springs 61 to the screen through the plugs 57, shafts 31, pulleys 29, tapes 32,
 80 pulleys 27, channel guide strips 33, and con-
 85 necting pins 39 to the top cross bar 40 at the upper end of the screen fabric 41. The side cases 22 are then attached to the sides of the window casing 20, the length of the pins 31 and 39 and the ends 55 permitting suffi-
 90 cient adaptation to insure a perfect fit with-
 95 in the window casing 20. The tension springs 61 hold the tension firmly on the roller 52 and the screen fabric 41 so that the screen fabric may be manually raised or lowered by the cross bar 40 as desired. The compensating notches 63 provide for the unequal stretching of the wire 41 or the
 100 tapes 32.

The locking plates 70 and the wrench 66 are provided with each screen so that it may be easily set up or taken down as desired thereby making a knock-down construction which is easily adjustable and operable.

I claim as new—

1. A screen of the class described comprising side cases having open lengthwise channels therein on the two opposite sides of the window casing, said side cases having open ended sidewise housings on their lower ends, and a crosswise roll case insertible into said sidewise housings to detachably connect said side cases.

2. A screen of the class described comprising a tubular roller, a plug revolvably mounted in each end of said roller, a coil spring in each end of said roller attached to said roller at one end and to one of said plugs of the other, each of said plugs having an opening in its outer end, a tube connecting said plugs within said springs, a revolvably mounted pulley at each end of said roller, an angular shaped pin attached to each of said pulleys to fit within said openings in the outer ends of said plugs to turn said plugs with said pulleys, a tape attached to each of said pulleys, a second pulley a spaced distance from each of said first mentioned pulleys, each of said tapes extending over said second pulley, a guide-piece attached to the end of each of said tapes, screen fabric attached to said roll at one end, and a cross-bar at the other end of said screen fabric detachably connected to said guide-pieces at each end.

3. In a screen of the class described, a side case having an open lengthwise channel on its inner side, said side case having a chute opening into said open lengthwise channel the full length thereof, a pulley revolvably mounted within said side case near each end thereof, a guide-piece slidably mounted in said chute, and a tape attached to said guide-piece and passing over said pulley at one end of said side case and attached to the pulley at the other end of said side case to be wound thereon, substantially as and for the purpose specified.
4. In a screen of the class described, a side case having an open lengthwise channel on its inner side, said side case having a chute opening into said open lengthwise channel the full length thereof, a pulley revolvably mounted within said side case near each end thereof, a guide-piece slidably mounted in said chute, a tape attached to said guide-piece and passing over said pulley at one end of said side case and attached to the pulley at the other end of said side case to be wound thereon, and means for holding said tape and pulleys from unwinding, substantially as and for the purpose specified.
5. In a screen of the class described, a side case consisting of a channel strip and a removable cover therefor providing an open lengthwise channel near one edge, said side case having a channel or chute the full length thereof opposite said open lengthwise channel, a guide-piece operably movable the full length of said chute, a pulley revolvably mounted at the top of said side case in line with said chute, a second pulley revolvably mounted near the bottom of said side case, guide pulleys above said bottom pulley and below said top pulley, and a tape attached to said guide-piece at one end and passing over said pulley at the top of said side case and attached to the pulley at the bottom of said side case to be wound around the same, substantially as and for the purpose specified.
6. In a screen of the class described, a side case comprising a channel strip and a cover attachable thereto forming a lengthwise channel therebetween for the edge of the screen fabric, an open ended housing extending out sidewise on the lower end of the side case cover, a pulley revolvably mounted on said channel strip opposite said open ended housing, a second pulley revolvably mounted on said channel strip near its upper end, a tape attached to said lower pulley to wind around the same and passing over said second pulley, and a guide-piece attached to the end of said tape and slidably mounted in said case opposite said lengthwise channel to be operably moved the full length of said side case by said tape.
7. A screen of the class described comprising side cases, a tape and pulleys operably mounted in each of said side cases, a roll case removably connected to said side cases, a tubular roller with screen attached thereto in said roll case, a plug revolvably mounted in each end of said roller, a coil spring within each end of said roller, said spring attached to said roller at one end and to one of said plugs at the other, one of said pulleys in each of said side cases revolvably mounted opposite each end of said roller, means for connecting and disconnecting said pulleys mounted opposite the ends of said roller and said plugs, and means for holding the tension of said springs and roller when disconnected from said side cases and for holding said pulleys and tape in position in said side cases when disconnected from said roller.
8. A screen of the class described comprising side cases consisting of channel strips for attaching to the frame and cover strips removably attached to said channel strips to form a vertical channel near one edge thereof, a lengthwise partition within said channel strip forming an inner channel or chute, pulleys revolvably mounted near the upper and lower ends of said channel strip, a tape attached to the pulley at the lower end and extending over the pulley at the upper end, a guide-piece fitted to slidably move within said inner channel or chute and attached to the upper end of said tape, a square pin attached to said lower pulley, a spring roller, screen fabric attached to said spring roller at one end and to said guide-piece at the other, said spring roll having an opening in the end thereof to removably receive said square pin, substantially as and for the purpose specified.
9. A screen of the class described comprising side cases having lengthwise channel openings therein for the edges of the screen fabric, pulleys revolvably mounted near the upper and lower ends of each of said side cases, a tape attached to the pulley at the lower end of each of said side cases to be wound thereon and extend over the pulley at the upper ends of each of said side cases, the upper ends of said tapes attached to guide-pieces slidably mounted within said side cases, a cross-bar removably attached to said guide-pieces on the upper ends of said tapes, said cross-bar and guide-pieces slidably movable by said tape to the upper and lower ends of said side cases, a roller case detachably connected to said side cases, a pin on each of said pulleys near the lower end of said side cases, a roller in said roll case, springs in said roller, plugs revolvably mounted in each end of said roller having openings therein to removably receive said pins on said pulleys, openings in said roller and plugs to receive a pin therethrough when disconnected, a locking

plate to hold said pulleys and tape in said side cases when disconnected, and screen fabric attached to said spring roller at one end and to said cross bar at the other and 5 slidably moving in said channel openings in said side cases, substantially as and for the purpose specified.

In testimony whereof I have affixed my signature in the presence of two witnesses.

WILLIAM W. WATSON.
